UNITED STATES PATENT OFFICE.

AUGUST FREDRICK ROSEN, OF MADISON, WISCONSIN.

RADIATOR.

1,076,704.

Specification of Letters Patent.

Patented Oct. 28, 1913.

Application filed May 14, 1912. Serial No. 697,163.

To all whom it may concern:

Be it known that I, AUGUST F. ROSEN, of Madison, Dane county, Wisconsin, have invented certain new and useful Improvements in Radiators, of which the following is a specification.

My invention relates to radiators for use in connection with steam, vacuum steam, or vapor heating systems and the object of 10 the invention is to provide means for automatically controlling the air relief and thereby regulate the radiation by controlling the number of sections in the radiator into which steam is admitted.

15 The invention consists generally in various constructions and combinations, all as hereinafter described and particularly pointed out in the claims.

In the accompanying drawings forming 20 part of this specification, Figure 1 is a side elevation, partially in section, of a steam radiator embodying my invention, Fig. 1^a is a side elevation, partially in section, of a steam radiator embodying my invention, 25 showing a modified construction, Fig. 2 is a vertical sectional view through one of the sections, of the modified construction, Fig. 3 is a horizontal sectional view on the line x—x of Fig. 2, Fig. 4 is a detail sectional 30 view of the valve by means of which the admission of the steam to the radiator sections is controlled, Fig. 5 is a detail sectional view of the check valve for preventing the return of air into the radiator when 35 the steam condenses.

In the drawings, 2 represents a steam supply pipe having a suitable valve 3. The radiator is shown as composed of a series of sections 4 connected with one another at 40 the bottom by suitable nipples 5. At the top the sections are connected by nipples 6 and provided with webs or walls 7 which close the passage between the adjoining sections. These webs have holes 8 therein into which 45 a thermostatic device, such as an expansion tube 9 is inserted. One end of this tube is anchored in the plug 10 in the outer section of the radiator. The tube 9 communicates through the plug 10 with an air pipe 11 connected with an air line pipe and provided with a valve 12 having a ball check 13 normally resting on a seat 14 and allowing the air to escape from the radiator but capable of being lifted to close the port 15 50 and prevent the passage of air from the system into the radiator as the steam con-

denses. The tube 9 is open at one end, communicating with the radiator sections in series and a valve 16, shown herein as conical in form, is mounted on a stem 17 provided with a hollow head 18 that is centrally mounted in a corrugated diaphragm 19 of suitable material, preferably copper, that is locked in the wall of the section by a suitable means, such as a ring 20. This diaphragm allows the movement of the valve 16 and dispenses with the usual packing. A stem 21 is tapped into the wall of a plug 21' and has an operating handle 22 and a flanged inner end 23 that is slidable in the head of the stem 17 against the tension of a spring 24. This spring is adapted to take up any strain or expansion after the valve has been seated and the valve 16 is thereby held on its seat with a yielding pressure. 75 The locking ring 20 is exteriorly threaded and is adapted to fit into an interiorly threaded recess in the end of the plug 21', the inner edge of the ring bearing on the edge of the diaphragm and locking it securely against the bottom of the recess.

Under the construction illustrated the sections under normal conditions of operation are heated in succession, the progressive heating being in proportion to the volume 85 of air displaced by the progressive flow of steam and allowed to pass off from the radiator. The tube 9 is heated progressively in degree from the steam inlet end of the radiator toward the other end of the radiator until the tube is expanded sufficiently 90 to close or shut off the escape of air from the radiator, the air which does not escape or exhaust serving as a cushion to check or hold back the steam and thus control the 95 number of radiator sections that may give forth their maximum efficiency. The number of sections heated will depend upon the position of the valve 16. If it is open a considerable distance, several sections of the 100 radiator will become heated before the expansion of the tube will be sufficient to close the opening and shut off the escape of the air. On the contrary, if the valve is only opened slightly, the escape opening will 105 soon be closed and only one of the sections will be heated before the air escape is cut off. In this way any number of the radiator sections may be heated by simply adjusting the relief valve, the air escape being 110 automatically closed and further entrance of steam into the radiator being prevented

by the air cushion. The steam entering the radiator will expand equally in all directions and being lighter than the air in the radiator, will rise in 5 the radiator sections successively, beginning with the first. The air will act as a cushion and will be forced upon the entrance of the steam toward the last section, while the steam will rise in the first section and contact 10 with the thermostatic tube, the air displaced being forced out through the open end of the tube in the last section. If there is sufficient pressure of steam, successive sections will be filled and an additional 15 length or surface of the thermostatic tube exposed to the steam until the expansion of the tube is sufficient to close the air exit opening and prevent further discharge of the air and thereby check the entrance of 20 steam into the remaining sections. The steam will enter the radiator only as fast as the air escapes and leaves room for it, and will expand and fill the sections regardless of the number of passages or loops there 25 may be in the sections. As soon as the first section is filled the steam expands in the same manner in the second, and so on until the radiator is filled or until the air exit is cut off. The expanding tube will close the 30 opening between it and the valve, thereby shutting off the escape of air, and the air remaining in the radiator will prevent the further entrance of the steam.

The inlet opening to the expansion tube 35 is preferably, as shown, in direct communication with the last section of the radiator or the one most distant from the steam supply pipe, and consequently communication with the other sections will be in series, the 40 air in the last section passing out first as the steam drives the air ahead of it from the section nearest the supply, the air escaping from the sections successively as long as the inlet to the tube is open. Evidently with a 45 little experiment, a person can adjust the closing valve and regulate to a nicety the number of sections to be heated.

In Figs. 2 and 3 I have shown a modified construction, which consists in providing 50 a wall 25 extending between the passages leading to adjoining sections and compelling the steam as it enters the section to flow to the top of the section on one side of the wall and down to the bottom of the section 55 on the other side of the wall before it can enter the passage leading to the adjoining section. With this construction the flow of steam upwardly through each section successively is insured. Each wall at the bottom 60 of the sections is preferably provided with a port 26 through which the water of condensation may flow back to the supply pipe, a sufficient amount of water remaining in the radiator to seal the ports 65 26 against the passage of steam therethrough.

The modified construction shown, involving the casting of the wall with the radiator, will add somewhat to the expense of the radiator, requiring special patterns, etc., and I therefore prefer the form illustrated in 70 Fig. 1, which may be easily embodied in the ordinary style of radiator in general use.

I do not wish to be confined to the form of relief valve shown or the manner of mounting it in the radiator, as in various 75 ways it may be changed and still be within the scope of my invention. Obviously, the radiator may be made in various sizes, the expansion tube operating in substantially 80 the same manner regardless of the number 85 of sections employed.

I claim as my invention:

1. A radiator comprising a plurality of sections, an expansion tube exposed to the steam within said sections and having an exhaust opening and an inlet opening communicating with said sections in series, and means for closing said inlet opening when said tube has expanded to a predetermined degree by contact with the steam in said sections. 90

2. A radiator composed of a series of sections and nipples connecting the sections at the bottom, nipples provided at the upper ends of said sections and having webs or 95 walls separating one section from the adjoining one, an expansion tube passing through said webs and having one end communicating with an air relief and its other end communicating with said sections in 100 series, a valve closing automatically the opening into said tube, said valve when open allowing air to flow into said tube, the opening into said tube being closed by said valve when said tube has expanded to a predetermined 105 degree by the flow of steam into said sections.

3. A radiator comprising a series of sections having ascending and descending passages therein and openings leading from one 110 section to another at the bottom of the radiator, means separating the passages of one section from the corresponding passages of the adjoining section at the top of the radiator, an expansion tube bridging the passages of said sections and exposed to the steam flowing therethrough, said tube communicating with an air relief and with said sections, and means for closing said tube when a predetermined number of sections 115 have been heated.

4. A radiator comprising a series of sections joined together, each section having a steam passage up one side and down on the other side of the section, means separating 120 the passages of adjoining sections at the top of the radiator, an expansion tube communicating with an air relief and passing through said separating means and adapted 125 to be expanded by contact with the steam 130

and having an open end within one of said sections, the air from the sections entering said tube and flowing therethrough to said air relief, and means for automatically closing said tube when expanded to a predetermined degree, for the purpose specified.

5. A radiator comprising a series of sections joined together, each section having a steam passage up one side and down the 10 other side of the section, one end of the passage communicating with the steam supply and the other with the adjacent section on the other side, means separating the passages of adjoining sections at the top of the 15 radiator, an expansion tube communicating with an air relief and with said sections in series and passing through said separating means and adapted to be expanded by contact with the steam, the air from the sections entering said tube and flowing therethrough to said air relief, and means for automatically closing said tube when expanded to a predetermined degree.

6. A radiator comprising a series of sections, an expansion tube disposed within said sections and exposed to the heat of the steam and having an exhaust opening and an inlet opening communicating with said sections in series, and a valve for closing the 30 inlet of said tube when it is expanded to a predetermined degree by contact with the

steam in said sections, said valve being adjustable to time the closing of said inlet opening and regulate the number of sections to which steam may be admitted.

35

7. A radiator comprising a series of sections having communicating passages at the bottom of the radiator and means separating said sections from one another at the top of the radiator, an expansion tube passing 40 through said separating means and having an air exhaust opening and an inlet opening communicating with said sections in series, said tube being exposed to the heating effect of the steam within said sections, and 45 means for closing said inlet opening when said tube is expanded to a predetermined degree.

8. A radiator comprising a plurality of sections, a thermostatic device exposed to 50 the steam within said sections and having an exhaust opening and an inlet opening communicating with said sections in series, said thermostatic device including means for closing said inlet opening under exposure of 55 said device to the steam in said sections.

In witness whereof, I have hereunto set my hand this 7th day of May 1912.

AUGUST FREDRICK ROSEN.
